UNITED STATES PATENT OFFICE.

FREDERICK F. BRUSH, OF LOS ANGELES, CALIFORNIA, ASSIGNOR TO ELEVATOR SAFETY APPLIANCE COMPANY, A CORPORATION OF CALIFORNIA.

INTERLOCK SYSTEM FOR ELEVATOR DOORS.

Application filed April 11, 1923. Serial No. 631,381.

To all whom it may concern:

Be it known that I, FREDERICK F. BRUSH, a citizen of the United States, residing at Los Angeles, in the county of Los Angeles and State of California, have invented a new and useful Improvement Comprising the Interlock Systems for Elevator Doors, of which the following is a specification.

My invention relates to elevators which 10 are used to transport persons and loads from one floor of a structure to another.

It is common practice to provide at each floor a door sliding in said structure which may be opened to give access to the elevator 15 when it is at that particular floor.

The principal object of the invention is to provide means for preventing the operation of the elevator at any time except when all the doors are entirely closed. By thus 20 preventing the operation of the elevator when any door is open or partly open, the liability of any person being caught and injured by the moving elevator is reduced to a minimum.

25 Further objects and advantages will be made evident hereinafter.

Referring to the drawing, Fig. 1 is a side elevation partly in section showing my invention.

30 Fig. 2 is a view from inside the car.

Fig. 3 is a plan view on an enlarged scale of the interlock mechanism at each door.

Fig. 4 is an elevation of same.

Fig. 5 is a section through one form of 35 elevator control switch.

Fig. 6 is a section on a plane represented by the line 6—6 of Fig. 5.

In the form of my invention illustrated, a building structure is shown having floors, 40 11, 12, 13 and 14. Serving these floors is an elevator car 15. At each floor a door 16 is provided, this door having a pin 17 on the top thereof. A crank shaft 20 is provided at each floor upon which is secured a 45 cam 21 so shaped as to be engaged and turned by the pin 17 as will hereinafter be explained.

Rigidly secured to and turning with each of the cams 21 is a crank 30 carrying a 50 crank pin or roller 31. This crank pin or roller 31 contacts with an arm 40 which has a hooked end 41, the arm 40 being keyed, or otherwise rigidly secured, on a main shaft 50. The main shaft 50 extends to the full 55 height of the elevator shaft and turns in

bearings 51, carried on plates 52 which are each secured by the building structure. Secured on the extreme lower end of the shaft 50 is an elevator control switch 60 which consists of an insulating casing 61 carrying segments 62 which may be connected by brushes 63 which are mutually connected and carried in an insulating member 64. The switch 60 is connected in the elevator circuit either directly or through 65 suitable controllers being used to inhibit the operation of the mechanism operating the car 15. A thrust bearing 70 may be provided at the bottom of the shaft 50 for taking all or a portion of the weight of 70 the shaft 50. Secured on the shaft 50 is a sheave 80 operated by means of a weight 81 through a cable 82 which passes over an idler sheave 83. A spring or other equivalent device may be provided as a substitute 75 for the parts 80 to 83, the purpose of which is to move the shaft 50 in a negative or counter clock device direction as viewed in Fig. 3, to throw the shaft 50 into what may be termed its normal position unless this shaft is otherwise restrained. The switch 60 is so arranged that when the shaft 50 is in its normal position the elevator circuit is completed and the elevator may then be operated through any suitable system of 80 control. When, however, the shaft 50 has been thrown in a positive direction from its normal position as shown in Fig. 3, the elevator circuit is broken.

For the purpose of throwing the shaft 50 in a positive direction, the mechanism illustrated in Figs. 3 and 4 is used at each door. The parts are shown in full lines in these figures in their normal position which is the position they assume when all the 95 doors are closed. It will be noted that the pin 17 is inside the cam 21 which is forked to receive this pin. When the door starts to open the initial movement of the door throws the cam 21 from the position shown in full lines in Fig. 3 into the position shown in dotted lines in that figure. The crank 30 rotates from its full line to its dotted line position thus throwing the arm 40 in a positive direction from its full line to 100 its dotted line position. With the parts in the position shown at dotted lines, the roller 17 is free to leave the cam but when it does so, it leaves the crank 30 in such a position that it locks the arm 40 in its dotted posi- 105 110

tion against the pull of the weight 81. This is accomplished by virtue of the hooked end 41 of the arm 40 engaging the roller 31, and the somewhat acute angle at which the 5 crank 30 and the arm 40 join, when extended, as shown in the dotted line. A pull of the arm 40 toward the crank 30 tends to lock the two together, since the hooked end of the arm prevents the crank from slipping 10 past. The movement of the arm 40 opens the switch 60 and holds it open until such a time as the door returns, the pin 17 then entering the cam 21 and throwing the parts back into their normal position.

15 It will be noted that when any door is opened, the main shaft 50 is rotated to open the switch 60 and that this switch will be held open until such time as that particular door is closed. It will therefore be seen 20 that to close the switch 60, it is essential that every door in the series be closed practically to its full extent thus insuring the safety feature shown.

I claim as my invention:

25 1. In an elevator: a structure having a plurality of floors; an elevator car serving said floors; a door at each floor closing an opening registering with said car when said car is at said floor; mechanism for operating said car; a device which when open inhibits the operation of said mechanism; a single vertical main shaft in said structure so connected to said device that a positive rotation of said shaft from its normal position will open said device; automatic means operated by a force independent of the movement of said doors for returning said shaft to its normal position when said shaft is free from external restraint; and a series of interlocks each operated by the initial movement of its associated door to positively rotate said shaft and hold said shaft when so rotated until said door is substantially closed.

45 2. In an elevator: a structure having a plurality of floors; an elevator car serving said floors; a door at each floor closing an opening registering with said car when said car is at said floor; mechanism for operating said car; a device which when open inhibits the operation of said mechanism; a single vertical main shaft in said structure so connected to said device that a positive rotation of said shaft from its normal position will open said device; automatic means for returning said shaft to its normal position when said shaft is free from external restraint; a crank shaft at each door; means which by a positive rotation of said 50 crank shaft turns said main shaft in a direction opposed to the action of said returning means; and means by which the initial movement of said door so turns said crank shaft.

65 3. In an elevator: a structure having a

plurality of floors; an elevator car serving said floors; a door at each floor closing an opening registering with said car when said car is at said floor; mechanism for operating said car; a device which when open inhibits the operation of said mechanism; a single vertical main shaft in said structure so connected to said device that a positive rotation of said shaft from its normal position will open said device; automatic means for returning said shaft to its normal position when said shaft is free from external restraint; a crank shaft at each door; a crank on each of said crank shafts; an arm on said main shaft at each door, each of said arms co-operating with one of said cranks to positively rotate said main shaft and to hold it against the action of said automatic means when so rotated; and means by which each door so operates its crank shaft.

4. In an elevator: a structure having a plurality of floors; an elevator car serving said floors; a door at each floor closing an opening registering with said car when said car is at said floor; mechanism for operating said car; a device which when open inhibits the operation of said mechanism; a single vertical main shaft in said structure so connected to said device that a positive rotation of said shaft from its normal position will open said device; automatic means for returning said shaft to its normal position when said shaft is free from external restraint; a crank shaft at each door; a crank on each of said crank shafts; an arm on said main shaft at each door, each of said arms co-operating with one of said cranks to positively rotate said main shaft and to hold it against the action of said automatic means when so rotated; and means by which each door so operates its crank shaft.

90 5. In an elevator: a structure having a plurality of floors; an elevator car serving said floors; a door at each floor closing an opening registering with said car when said car is at said floor; mechanism for operating said car; a device which when open inhibits the operation of said mechanism; a single vertical main shaft in said structure so connected to said device that a positive rotation of said shaft from its normal position will open said device; automatic means for returning said shaft to its normal position when said shaft is free from external restraint; a crank shaft at each door; a crank on each of said crank shafts; an arm on said main shaft at each door, each of said arms co-operating with one of said cranks to positively rotate said main shaft and to hold it against the action of said automatic means when so rotated; a cam secured to each of said crank shafts; and

means by which each door operates its cam.

6. In a safety device for elevators, the combination of: a substantially vertical shaft; a control member operated through the rotation of said shaft; a series of lever arms mounted along said shaft in positions adjacent to elevator doors; and means actuated by said doors at the initial opening movement thereof, in a manner to exert a ro-

tative force against said lever arms so as to rotate said shaft, said arms being returnable to the position occupied before rotation by a force independent of the movement of said doors.

In testimony whereof, I have hereunto set my hand at Los Angeles, California, this 5th day of April, 1923.

FREDERICK F. BRUSH.
